(57) **CLAIM**

The ornamental design for jewelry with faux drill bit, as shown and described.

DESCRIPTION

FIG. 1 is a side view of jewelry with faux drill bit, showing my new design, with the opposing side a mirror image thereof;

FIG. 2 is a front view thereof;

FIG. 3 is a rear view thereof;

FIG. 4 is top plan view thereof;

FIG. 5 is a bottom plan view thereof;

FIG. 6 is a bottom perspective view thereof;

FIG. 7 is a bottom view of the ring seen in FIGS. 1-6, having a smooth upper inside dome, with the remaining views correspondent to those FIGS. 1-4 and 6;

FIG. 8 is a top view of jewelry with faux drill bit showing my new design, and having a stone set in the faux drill bit. Remaining views are correspondent to those of FIGS. 1-3, 5 and 6 or 7;

FIG. 9 is a side view of a second embodiment of jewelry with faux drill bit, which correspond to the views of FIGS. 1-4, but with stones mounted on the outside, with the opposing side a mirror image thereof;

FIG. 10 is a front view of FIG. 9, with remaining views correspondent to those FIGS. 5 and 6 or 5 and 7;

FIG. 11 is a rear view of FIG. 9, with remaining views correspondent to those FIGS. 5 and 6 or 5 and 7; and,

FIG. 12 is a top plan view of FIG. 9, with remaining views correspondent to those FIGS. 5 and 6 or 5 and 7.
